UNITED STATES PATENT OFFICE

FRANK LOUIS MILLER, OF PARKERSBURG, WEST VIRGINIA, ASSIGNOR TO DAVIS-MILLER ENGINEERING COMPANY, OF PARKERSBURG, WEST VIRGINIA, A CORPORATION OF WEST VIRGINIA

SEMITRAILER

Application filed February 8, 1931. Serial No. 513,218.

This invention relates to semi-trailers, and more particularly to means for operating the front supporting wheels of such devices whereby they may be moved between operative and inoperative positions and supported in such positions.

An important object of the invention is to provide operating bars connected at one end to the axles or struts of the forward supporting wheels of a semi-trailer and operative for swinging the struts whereby the wheels may be moved between operative and inoperative positions.

A further object is to provide novel means for locking the operating bars in either of their two positions.

A further object is to provide the operating bars with rack teeth, and to provide novel pinion operated means for the rack bars whereby the latter are adapted to move the front supporting wheels of a semi-trailer between operative and inoperative positions.

A further object is to provide a device of the character referred to which is extremely simple in construction and which is adapted to effectively hold the supporting wheels in operative position when desired.

Other objects and advantages of the invention will become apparent during the course of the following description.

In the drawings I have shown one embodiment of the invention. In this showing,

Figure 1 is a fragmentary plan view of a portion of the supporting frame of a semi-trailer showing the invention applied,

Figure 2 is a side elevation of the same,

Figure 3 is a front elevation of the same,

Figure 4 is a section on line 4—4 of Figure 1, and,

Figure 5 is an enlarged fragmentary sectional view on line 5—5 of Figure 1.

Referring to Figures 1, 2 and 3, the numeral 10 designates a pair of side rails forming the supporting frame of a semi-trailer, and the rear end of the trailer is supported by the usual wheels (not shown). Each side rail is provided near its forward end with a stub shaft 11 secured to the rail by a nut 12. Each stub shaft pivotally supports a hanger 13 to which are secured the upper ends

of struts 14. The struts are preferably channel-shaped to receive the depending end of the hanger 13, and the latter is provided with a series of openings 15 selectively receiving bolts 16 by means of which the struts may be secured to the hangers in any desired adjusted position with respect thereto. The hangers may be maintained in position on the stub shafts by cotter pins 17.

An axle 18 is arranged across the bottom of the struts 14. Base plates 19 seat against the lower ends of the struts and upon the top of the axle 18, and the base plates are secured to the axle by means of U-bolts 20. The base plates carry upwardly extending portions 21 which are arranged in the channels of the struts and are secured to the struts by bolts 22. Supporting wheels 23 of the usual type are carried by the outer ends of the axles 18 and are held in position by nuts 24.

Each base plate 19 carries a pair of preferably integral upwardly and rearwardly extending ears 25 and each pair of ears carries a pivot pin 26 secured against longitudinal movement with respect to the ears by cotter pins 27. The forward ends of bars 28 are arranged between the ears 25 and are pivotally connected to the pins 26. Each of the bars 28 carries rack teeth 29, as clearly shown in Figures 2, 4 and 5, and one of the bars is further provided with a pair of openings 30 for a purpose to be described.

Each side rail 10 carries a depending bracket 31 secured thereto by bolts 32 and arranged a substantial distance rearwardly of the stub shafts 11. Each bracket 31 rotatably supports a stub shaft 33 having a polygonal outer end 34. The two stub shafts 33 are connected by a tubular member 35 secured to the stub shafts by pins 36.

A keeper 37 is associated with each bar 28. Each keeper includes a top plate 38 seating against the top of the associated bar 28, and a depending side plate 39 surrounding the associated shaft 33. At the other side of each keeper U-bolts 40 extend through the top plate 38 and around the shaft 33. Within each keeper 37, a pinion 41 is keyed or otherwise secured to the associated shaft 33 to be rotated thereby, and the pinions mesh with

the rack teeth 29, as clearly shown in Figure 5.

Means are provided for retaining the rack bars in either of the two positions to which they are adapted to be moved upon rotation of the pinions 41. Such means may be associated with both of the rack bars, but only one of the holding means may be employed, as illustrated in the drawings. Referring to Figure 5 the numeral 42 designates a flat resilient plate riveted or otherwise secured at one end to one of the keeper plates 38 as at 43. The opposite end of the plate 42 is offset outwardly of the keeper and extends beyond the lower end thereof to form a handle 44. Inwardly of the handle the plate 42 is provided with a locking finger 45 extending through an opening 46 in the plate 38, the finger 45 being secured to the plate 42 by upper setting or riveting the upper end of the finger as at 47. The finger 45 is adapted to be arranged in either of the openings 30 of the associated rack bar 28.

An upwardly extending bolt 48 is secured to the keeper plate 38 with which the locking plate 42 is associated, and the bolt 48 has a nut 49 threaded on its upper end. A coil spring 50 surrounds the bolt 48 between the nut 49 and the plate 42 to maintain the latter in the operative position shown in Figure 5.

The operation of the device is as follows:

During the operation of the semi-trailer, the wheels 23 and struts 14 normally occupy the dotted line position shown in Figure 2, as will be apparent. When the parts are in the position referred to, the locking finger 45 is in engagement with the lower opening 30 whereby it will be apparent that movement of the rack bars will be prevented, and accordingly the wheels 23 will be locked in inoperative position.

In this connection, it will be noted that the pinions 41 are fixed against rotation with respect to each other by the connections between the stub shafts 33 and the sleeve 35. The locking of one rack bar against movement, therefore, also prevents any movement of the other rack bar. It will be apparent, however, that separate locking means for each rack bar may be provided if desired.

When it is desired to disconnect the semi-trailer from the truck, the latch handle 44 is moved upwardly to move the free end of the plate 42 against the tension of the spring 50 and release the locking finger 45 from engagement with the lower opening 30. The wheels 23 and struts 14 then may be moved downwardly to the operative position shown in Figure 2, and when the parts reach such position, the locking finger 45 will snap downwardly into the upper opening 30. The parts thus will be locked in operative posi-

tion until it is again desired to connect the semi-trailer to the truck.

The parts may be moved very readily to inoperative position by lifting the latch handle 44 and rotating the stub shafts 33. In this connection it will be noted that rotation of the stub shafts 33 may be readily accomplished by the use of a suitable handle having a socket to receive either of the polygonal shaft ends 34. The stub shafts 33 may be rotated in the manner referred to to rotate the pinions and thus move the rack bars upwardly and forwardly until the locking tooth 45 snaps into the lower opening 30 to retain the parts in inoperative position.

It will be apparent that the keepers 37 are pivoted to swing about the axis of the stub shafts 33. Accordingly these keepers are adapted to act as bearings for the rack bars and they alter their positions during movement of the rack bars in accordance with the change in angularity of these elements as they are moved between operative and inoperative positions.

From the foregoing it will be apparent that the present device is quite simple in construction and may be cheaply manufactured. It also will be apparent that the device may be operated very readily and that the locking means employed is effective for retaining the forward supporting wheels in either of their two positions.

It is to be understood that the form of the invention herewith shown and described is to be taken as a preferred example of the same and that various changes in the shape, size and arrangement of parts may be resorted to without departing from the spirit of the invention or the scope of the subjoined claims.

I claim:

1. In a semi-trailer, depending strut means pivotally connected to the body of the trailer to swing between operative and inoperative positions and provided with supporting wheels, a rack bar pivotally connected at one end to said strut means, a pinion meshing with the teeth of said rack bar at a point spaced from said strut means, and means for locking said strut means in either of said positions.

2. In a semi-trailer, depending strut means pivotally connected to the body of the trailer to swing between operative and inoperative positions and provided with supporting wheels, a rack bar pivotally connected at one end to said strut means, a guide for said rack bar, a pinion arranged adjacent said guide and meshing with the teeth of said rack bar at a point spaced from said strut means, and means for locking said strut means in either of said positions.

3. In a semi-trailer, depending strut means pivotally connected to the body of the trailer to swing between operative and in-

operative positions and provided with supporting wheels, a rack bar pivotally connected at one end to said strut means, a guide keeper for said rack bar pivoted to alter its position in accordance with the angular position of said rack bar, a pinion rotatable about the pivot axis of said keeper and meshing with the teeth of said rack bar, and means for locking said strut means in either of said positions.

4. In a semi-trailer, depending strut means pivotally connected to the body of the trailer to swing between operative and inoperative positions and provided with supporting wheels, a rack bar pivotally connected at one end to said strut means, a pinion meshing with the teeth of said rack bar at a point spaced from said strut means, said rack bar being provided with an opening, a pin adapted to be arranged in said opening to lock said rack bar against movement, and resilient means normally urging said pin toward said opening.

5. In a semi-trailer, depending strut means pivotally connected to the body of the trailer to swing between operative and inoperative positions and provided with supporting wheels, a rack bar pivotally connected at one end to said strut means, a pinion meshing with the teeth of said rack bar at a point spaced from said strut means, said rack bar being provided with an opening, a guide for said rack bar maintaining the teeth thereof in engagement with said pinion, said rack bar being provided with a pair of openings, a pin carried by said guide and adapted to be selectively arranged in said openings to retain said rack bar in either of its two positions, and resilient means tending to urge said pin toward operative position.

6. A device constructed in accordance with claim 5 wherein said guide is pivotally supported whereby it is adapted to alter its position in accordance with the angular position of said rack bar.

7. In a semi-trailer, a pair of depending parallel struts pivotally connected at one end to the body of a trailer to swing between operative and inoperative positions, an axle, supporting wheels carried by said axle, means for securing said axle to the other ends of said struts, a pair of rack bars connected at one end to said securing means, a pinion meshing with the teeth of each rack bar, means connecting said pinions rigidly to each other, and means for locking one of said struts in either of its two positions.

8. In a semi-trailer, a pair of depending parallel struts pivotally connected at one end to the body of a trailer to swing between operative and inoperative positions, an axle, supporting wheels carried by said axle, means for securing said axle to the other ends of said struts, a pair of rack bars

connected at one end to said securing means, a pinion meshing with the teeth of each rack bar, means connecting said pinions rigidly to each other, one of said rack bars being provided with a pair of openings, and a locking pin engageable in either of said openings for locking said last named rack bar against movement in either of said positions.

9. A device constructed in accordance with claim 8 provided with a guide for each rack bar arranged adjacent each pinion and adapted to swing about the axis thereof, a plate connected at one end to one of said guides, said pin being connected to the other end of said plate, and spring means operating against said plate to urge said pin toward operative position.

In testimony whereof I affix my signature.
FRANK LOUIS MILLER.
